UNITED STATES PATENT OFFICE.

AKSEL SUNDE, OF SIOUX CITY, IOWA.

SASH-LOCK.

1,186,861.

Specification of Letters Patent. Patented June 13, 1916.

Application filed March 11, 1916. Serial No. 83,632.

To all whom it may concern:

Be it known that I, AKSEL SUNDE, a citizen of the United States, and a resident of Sioux City, in the county of Woodbury and State of Iowa, have invented certain new and useful Improvements in Sash-Locks, of which the following is a specification.

The present invention relates to window sash-locks.

10 The invention has for its primary object the production of an improved lock, particularly designed for use upon vertically movable window sash, and adapted to lock the lower sash against vertical movement from any point.

15 A further object of the invention is the production of an improved sash-lock, inexpensive in manufacture, readily attachable and highly efficient in operation.

20 With these and other objects in view the invention, consisting in the construction, combination and novel arrangement of parts, will be fully understood from the following description, reference being had to 25 the accompanying drawings, which form a part of this application and in which like characters of reference indicate corresponding parts throughout the several views, of which,—

30 Figure 1 is a transverse section of a pair of window sash, equipped with the preferred embodiment of my invention; Fig. 2 is an enlarged side elevation of the lock, the flexible link being cut away; Fig. 3 is a front elevation of the same; Fig. 4 is a vertical section of the same; and Fig. 5 is a plan of Fig. 3.

35 Although I have illustrated and herein-after described the preferred embodiment of the invention, I would not be understood as being limited to the specific structure chosen for illustration, for various alterations and modifications in the details of construction and arrangement of parts may be made 45 without departing from the spirit and scope of the invention as defined in the appended claims.

40 The invention contemplates, broadly, a lock including a suitable case adapted to 50 be mounted on the lower sash, and having rotatably mounted therein a retractable spring roller, upon which is wound a flexible tape, the free end of which is adapted to be secured to the upper sash and detent

mechanism operable to engage the link and 55 prevent unwinding thereof all of which will be presently made clear.

Referring now to the illustrations, 6 and 7 are upper and lower window sash, respectively, each having the usual side members 8, and transverse members, 9. The window panes are represented at, 10. Upon the upper cross member of the lower sash is mounted a suitable case, 11, preferably arch-shaped in general contour and having a 65 base, 12, adapted to be secured to the side cross member. The case incloses a roller, 13, mounted on axis, 14, journaled in bearing openings, 15, in opposite sides of the case. The roller is provided on one side with an 70 annular shoulder, 16, upon which is wound a spiral spring, 17, one end of which is secured to the case, as at 18. Upon the roller, 13, is wound a perforated steel tape, 19, one end of which is fast to the roller. The tape 75 passes freely through a slot, 20, in the lower portion of the case and its lower end is riveted or otherwise secured, as at, 21, to a flanged plate, 22, mounted on the upper side of the lower cross member of the upper sash. 80 Upon the side of the case is mounted a detent operable to engage the tape and preferably comprising a bell-crank lever, 23, fulcrumed at, 24. The depending arm of the lever is off-set below the case, as at 25, and provided with a stud, 26, adapted to enter the perforations of the tape. The other end of the lever may be provided with a lateral knob, 27, for conveniently manipulating the lever. The weight of the lever tends to hold 85 the stud, 26, in engagement with the tape. The detent may be held out of engagement with the tape by moving the lever to the position shown in dotted lines in Fig. 2 and springing it over a stud, 28, on the side of the 90 case, which prevents downward movement of the lever. Upon one end of the flanged plate, 22, may be pivoted a hook-arm, 29, the hook of which is engageable (when the lower sash is closed) with a head, 30, on the base 95 of the case, thereby preventing opening of either sash. It is now evident that the stud, 26, prevents unwinding of the tape and thereby prevents upward movement of the lower sash; yet the said sash may be readily 100 lowered when in opened position, as the stud, 26, is so inclined as to slip out of the perforations when the sash is thus moved.

Having thus described my invention, what I claim as new and desire to secure by Letters Patent, is,—

1. A lock for a window having an upper and a vertically movable lower sash, comprising a case adapted to be mounted on the top of the lower sash, and having a slot in its under side, a retracting roller rotatably inclosed by the case, a perforated tape wound on the roller and passing through said slot, the free end of the tape being adapted to be secured to the lower part of the upper sash, and a lever fulcrumed on the case and having a depending arm extending below the case and pro-

vided with an upwardly-inclined stud engageable with the perforated tape.

2. A lock for a window having an upper and a vertically movable lower sash, comprising a case adapted to be mounted on the top of the lower sash, a retracting roller rotatably inclosed thereby, a perforated tape wound on the roller and adapted to be secured to the lower part of the upper sash, and a detent operable to engage and prevent unwinding of the tape.

In testimony whereof I have hereunto set my hand.

AKSEL SUNDE.
